R. E. McGAHEY.
SELF LOCKING ANGLE COCK.
APPLICATION FILED NOV. 15, 1919.

1,351,391.

Patented Aug. 31, 1920.

Attorney

UNITED STATES PATENT OFFICE.

ROBERT E. McGAHEY, OF ALEXANDRIA, VIRGINIA.

SELF-LOCKING ANGLE-COCK.

1,351,391.

Specification of Letters Patent. Patented Aug. 31, 1920.

Application filed November 15, 1919. Serial No. 338,203.

To all whom it may concern:

Be it known that I, ROBERT E. McGAHEY, a citizen of the United States, residing at Alexandria, in the county of Alexandria 5 and State of Virginia, have invented certain new and useful Improvements in Self-Locking Angle-Cocks, of which the following is a specification.

This invention relates to self-locking angle cocks and has for an object to provide 10 a cock of the kind having improved means for locking in either open or closed condition, and when in open condition to position the handle under the car to which the device is attached and under the train pipe.

With these and other objects in view, the device comprises certain new and novel units, elements, combinations and arrangements of parts as will be hereinafter more 20 fully described and claimed.

Referring to the accompanying drawings, which are made a part hereof, and on which similar reference characters indicate similar parts,

25 Figure 1 is a view of the device in side elevation;

Fig. 2 is a view of the device in inverted plan as indicated by arrow 2 at Fig. 1;

Fig. 3 is a perspective view of the locking 30 handle member; and

Fig. 4 is a perspective view of the rotating disk.

The improved angle cock, which forms the subject matter of this application, comprises 35 a body 10 of any approved type, containing a valve or cock of the turning plug type, the exact construction of which forms no part of the present invention. The housing is provided with a multiangular extremity 11 here shown as hexagonal, adapted to be attached to the train pipe 12 under a car indicated at 13. At its opposite downwardly inclined end, the cock is provided with an internally threaded sleeve 14 adapted to receive 40 a nipple 15 attached to the flexible pipe 16 in the usual well known manner.

The turning plug is provided with a stem 17 to which is secured a disk 18 in any approved manner, as by a pin through the 50 opening 19 of the disk, and through the stem of the plug.

The housing 10 has preferably cast integral therewith a segment 20, having stops 21 and 22, and a slot 23 proportioned and 55 positioned to receive the lug 24 on the disk 18.

A handle 25 is provided with a collar portion 26, proportioned to embrace disk 18 and to be pivoted thereto as at 27. The handle is also provided with one or more lugs 28 proportioned to engage in the openings 29 in the segment 20. As shown in the drawings, the lugs are two in number and the openings 29 are in groups of two at open and closed position, it being understood, however, that the number of lugs and openings in each group is immaterial to the invention. The handle is also provided with a slot 30 proportioned to pass over the lug 24 as indicated more particularly at Figs. 1 and 3. 60 65 70

In operation, when the cock is open to permit the passage of air through the train pipe and couplings, the handle 25 is disposed longitudinally directly under and substantially paralleled with the train pipe 12. When 75 the cock is to be closed, it is necessary to lift the handle from the position shown in Fig. 1 to release the lugs 28 from the openings 29, and swing the handle one quarter of a turn to engage the lugs 28 in the other group of 80 openings 29. In either open or closed position, the weight of the handle 25 will hold lugs 28 in locking engagement with the openings 29. The stops 21 and 22 engage against the handle at either limit of its 85 movement, also the lug 24 engages the extremities of the slot 23 for a similar purpose.

The position of the handle longitudinally beneath the train pipe is important to the 90 present invention, for the reason that, with the handles of the cocks located otherwise especially as at present employed, it is in position to be accidentally closed to shut off air from the train. This has happened many 95 times when unauthorized persons are boarding a car and step upon the cock handle. The cutting off of the air to the train results in accidents and the present invention is intended as adding to the safety of operation 100 with air brakes.

Having thus fully described my said invention, what I claim as new and desire to secure by Letters Patent, is:

1. An angle cock comprising a housing, a turning plug, a segmental flange formed upon the housing and provided at either extremity with a stop and having a segmental slot formed in its face, a disk rigidly secured to the turning plug and having a lug fitting and movable in the slot, a handle member provided with a collar embrac-

105

110

ing the disk and proportioned to engage against the stops at each limit of movement, and a lug carried by the handle adapted to engage an opening in the segmental flange at 5 either limit of movement.

2. The combination with a train pipe, of an angle cock secured thereto and extending therebeyond, said angle cock comprising a housing connected with the train pipe, 10 a turning plug rotatable in the housing, and a handle secured to the turning plug and positioned beneath and in parallelism with the train pipe when communication is established through the cock, and at right angles 15 to and extending laterally beyond the train pipe when communication is interrupted.

3. The combination with a train pipe of an angle cock secured thereto and comprising a housing in communication with the 20 train pipe, a turning plug mounted to rotate in the housing, a handle pivotally connected with the turning plug and adapted to swing upon the pivot on a variable plane constantly in parallelism with the axis of rotation of the plug and so positioned that 25

when communication is established through the cock the handle is disposed beneath and in parallelism with the train pipe, and means carried by the handle employing the weight of the handle for locking the cock 30 in open and closed position.

4. The combination with a train pipe, of an angle cock secured thereto and extending therebeyond, said angle cock comprising a housing connected with the train pipe, 35 the housing being provided with a segmental flange having a segmental slot formed in its face, a turning plug rotatable in the housing, and a handle secured to the turning plug and positioned beneath and in parallelism with the train pipe when communication is established through the cock, and at right angles to and extending laterally beyond the train pipe when communication is interrupted. 40

In witness whereof, I have hereunto set my hand and seal at Washington, D. C., this 15th day of November, A. D., nineteen hundred and nineteen.

ROBERT E. McGAHEY. [L.S.]
